OVERHEAD CARRIER SYSTEM

Morris G. Rosenthal, Cleveland, Ohio, assignor
to The Cleveland Crane & Engineering Com-
pany, Wickliffe, Ohio, a corporation of Ohio

Application September 20, 1937, Serial No. 164,684

6 Claims. (Cl. 104—172)

The present invention relates to material handling tram-rail systems having portions thereof provided with a chain or similar power drive for moving carriers thereon. More particularly, the invention relates to a means for connecting the carriers to the power drive.

In systems of the character referred to, the power drive, which is usually applied to only a part of the system, is operated at a constant speed, and when the driving dogs or the like thereof engage or pick up a stationary or slowly moving carrier pushed or otherwise moved into that part of the system provided with the power drive, the impact and instantaneous acceleration of the carrier subjects the system to tremendous strain which, in many instances, results in damage to the system and failure thereof interrupting the operation of which it is a part. This is especially true where the carriers are heavily loaded, as is most often the case. Again, if the free movement of one or more of the carriers connected to the drive is interfered with, for any reason, such as insufficient clearance in the aisles through which the carriers or the racks, etc., upon which the load is placed move, or in the event one or more of the wheels of the carrier becomes caught in an improperly thrown switch, serious damage often results.

The purpose of the present invention is to overcome the aforesaid and other defects of the prior art tramrail systems and the principal object of the present invention is the provision of a tramrail system of the type referred to, that is, one having at least a portion thereof provided with a chain drive or similar power, for moving carriers thereon, which will be simple in construction, easily maintained and operated, and in which carriers moved onto the section provided with the drive will be slowly accelerated to the speed of the drive without subjecting the system to serious strain, and in which the carriers will be readily disconnected from the power drive in the event that their free movement is interfered with for any reason.

Another object of the present invention is the provision of a novel device for connecting the carriers of a tramrail system of the character referred to to a continuously moving chain or similar power drive, which device will gradually accelerate a carrier to the speed of the power drive without imposing undue strain upon the system, and which will permit the connection between the carrier and the drive to be broken in the event that the free movement of the carrier is interfered with for any reason.

The present invention resides in certain novel details of construction, and combinations and arrangements of parts, and further objects and advantages thereof will be apparent to those skilled in the art to which the invention relates from the following description of the preferred embodiment thereof described with reference to the accompanying drawings, forming a part of this specification, in which similar reference characters designate corresponding parts throughout the several views, and in which:

Fig. 1 is a schematic view of an overhead tram-rail system embodying the present invention;

Fig. 2 is a view taken on the line 2—2 of Fig. 1 looking in the direction of the arrows;

Fig. 3 is a view taken on the line 3—3 of Fig. 2 looking in the direction of the arrows;

Fig. 4 is a view taken on the line 4—4 of Fig. 2 looking in the direction of the arrows, and

Fig. 5 is a section on the line 5—5 of Fig. 3 looking in the direction of the arrows.

While the invention is susceptible of various modifications and alternative constructions it is herein illustrated and described as embodied in an overhead tramrail system of the mono-rail type. For the most part the tramrail system herein referred to is commercially known in the art and only those parts thereof which are necessary to the complete understanding of the present invention will be herein illustrated and described in detail.

Referring to the drawings, Fig. 1 shows schematically a portion of an overhead tramrail system of the monorail type embodying the present invention and comprising a main loop designated generally by the reference character A, a side loop B, and by-pass or branch lines C, and D. The tramrail system shown includes automatic dispatch mechanism, that is mechanism for sending carriers automatically to predetermined stations, but the present invention is equally applicable to other types of systems as will be herein-after apparent. The main loop A comprises an overhead monorail track or rail 10 supported in any convenient manner as by being suspended from a structural member 11 which may be part of the superstructure of the building in which the system is located. The supporting mechanism forms no part of the present invention and is entirely omitted from Fig. 1.

The carriers, designated generally by the reference character E, may be of any commercially known construction suitable for the purpose for which they are intended. As shown they comprise a load bar 12 carried by a pair of trucks,

the wheels 13 of which engage the treads of the track on rail 10, and a rack 14 upon which the material or load is placed. The carriers are adapted to be moved along the track 10 of the 5 main loop by driving dogs, designated generally by the reference character F, which engage behind a part of the carrier and push or pull the same along the track. The dogs F form a part of a continuously moving power drive and will 10 be hereinafter more specifically referred to.

The side loop B, for example, may be one of a plurality of stations at which certain operations are performed on articles supported on the carriers E or it may be a station at which the carrier is loaded or unloaded. The branch lines C and D may lead to such places as storage, other loops, etc. Carriers are transferred from the main loop A to the side loops, or to the branch lines, etc., through the medium of transfer 15 switches designated generally by the reference character G, which switches may be of any commercially known construction and are not herein illustrated and described in detail. Because the present system is of the automatic dispatch type 20 the switches G, with the exception of the switch designated G' leading from the side loop to the main loop, are electrically operated and automatically controlled by limit switches 16 and 17 located at opposite sides of the respective transfer 25 switches. The actuation of the limit switches is controlled by the carriers moving on the system. For the purpose of selecting the particular station or branch line, etc., to which the carriers are dispatched the carriers are provided with 30 means for selectively actuating the limit switch 16 located at the approaching side of the transfer switches G. In the present instance this mechanism comprises a tripper arm 18 fixed to the load bar 12 of the carrier and having a plurality 35 of holes therein for the location of a station tripper cam 19 adapted to strike or engage the arm 20 of the limit switch 16 and thus operate the same. Different arms 20 are located at different 40 distances from the track 10 to correspond to different locations of the tripper cam 19 along the tripper arm 18. The rack 14 is swivelly connected to the load bar 12 so that the swing of the carrier as it travels about curves, etc., will 45 not move the tripper cam out of the path of the limit switch arms 20.

Assume that the operator located at the station or side loop B is finished with the carrier E located therein and wishes to dispatch it to some other station, after setting the ripper cam 19 in the proper hole to select the desired station or branch line, he operates the manually controlled transfer switch G' and pushes the carrier out onto the main loop, first observing that the approaching dog F is unloaded, after which he 55 turns the switch G' to its original position. Usually the drive is traveling at a fairly fast rate of speed and when the the dog engages the carrier, which is stationary, the impact incident thereto subjects the system to considerable 60 strain, often resulting in serious damage and failure of the system.

According to the provisions of the present invention novel means is provided for operatively connecting the power drive to the carrier, which 65 means will not only relieve excess strain due to impact as the drive engages the carrier but will also disconnect the carrier from the drive in the event that the free forward movement of the carrier is interfered with, in other words, in the 70 event the force required to move the carrier

along the track exceeds a predetermined amount. In the embodiment of the invention shown this means comprises the driving dogs F, previously referred to, connected at spaced intervals to the flexible driving element which as shown is a 5 roller chain 22, continuously driven in any convenient manner by a sprocket wheel and an electric motor, not shown. Each of the driving dogs 10 comprises a pawl or ratchet member 25, see Fig. 4, pivotally supported by a pin 26 projecting through aligned apertures in members 27 and 28 15 welded to a lever comprising spaced upper and lower members 29 and 30. The front end of the ratchet member 25 is formed to engage a portion of the carrier. As shown the ratchet member 25 20 engages a bracket arm 31 welded or otherwise fixed to the end of the tripper arm opposite to the end thereof which carries the station tripper cam 19. The forward end of the ratchet member 25 is heavier than the other end which causes 25 it to normally assume a position to engage the bracket arm 31, that is, the position shown in full lines in Fig. 4, but the construction is such that a carrier can be pushed ahead of a dog if desired. In this event the bracket arm 31 on 30 the carrier engages the inclined edge X of the ratchet member, raising the ratchet member to the position shown in dotted lines in Fig. 4, and passing freely thereunder. After the bracket member 25 the latter returns to its normal position and is ready to pick up the carrier and carry it about the system.

The forward end of the lever comprising the members 29 and 30 is pivotally connected to one 35 end of a lever comprising upper and lower spaced members 33 and 34 and spacer collars 35 and 36 interposed between the latter, through the medium of a pivot pin 37. The center of the lever comprising the spaced members 33 and 34 is 40 pivotally connected to a frame comprising spaced upper and lower plates 38 and 39 suitably secured together, by means including a long pin 40 fixed to or carried by a truck 41, the wheels 45 of which are adapted to travel along the flanges of a track or rail 42 paralleling the rail or track 10 and secured to structural members 43 in any convenient manner. The pin 40 projects downwardly from the truck 41 through a link 22 of the flexible driving element which in the present 50 instance is a roller chain, through a spacer member 45, upper plate 38, upper member 33, spacer collar 36, lower member 34, lower plate 39, and a guide wheel 46 rotatably secured to the lower end thereof as by a nut 47. The guide wheel 46 runs 55 between angle arms 48 and 49 connected to the supporting structure in any suitable manner.

The rear end of the lever comprising the spaced members 29 and 30 is pivotally connected to one 60 end of a lever comprising upper and lower spaced members 50 and 51, and spacer collars 52 interposed between the latter, by a pivot pin 53. The other end of the lever comprising the spaced members 50 and 51 is pivotally connected by a long pin 54 to the frame comprising the spaced 65 plates 38 and 39 in a manner similar to that in which the lever comprising the spaced members 33 and 34 is connected to said frame. The pivot pins 40 and 54 are in line with the direction of travel indicated by the arrow y in Figs. 1 and 3. 70

The right hand end, as viewed in Fig. 3, of the lever comprising the spaced members 33 and 34 is 75 pivotally connected through the medium of a pin 55 to one end of a rod 56. Spacer collars 57 positioned about the pin 55 on opposite sides of the rod

56 locate the latter centrally of the members 33 and 34. The rear end of the rod 56 projects through a suitable aperture in a disk-like member 58 slidably supported in a tubular member 59 5 pivotally supported between the plates 37 and 38 by trunnions 60 fixed in the wall of the member 59, as by being welded in suitable apertures formed therein. A nut 61 threaded onto the rear end of the rod 56 retains the disk 58 thereon. 10 The forward end 62 of the member 59 through which the rod 56 projects is closed except for the opening through which the rod 56 projects. The member 59 forms a housing for a coil spring 65 15 interposed between the member 58 and the closed end 62 of the member 59. The spring 65 may be of any suitable strength and the nut 61 permits limited adjustment thereof. Rotation of the lever comprising the members 33 and 34 in a 20 counterclockwise direction as viewed in Fig. 3 is limited by the engagement of the ends of the pin 55 with the forward edge of the plates 37 and 38 which are cut back as clearly shown in Fig. 3 in such a manner that the longitudinal axis of the lever is normally at right angles to the direction of 25 travel.

From the foregoing description of the dog F it is thought that the operation thereof will be apparent. Suffice it to say that as the ratchet member 25 strikes the bracket arm 31 on a stationary 30 carrier the former will yield slightly compressing the spring 65 and relieving the system, especially the power drive, of excessive strain. The amount that the ratchet arm 25 will yield will depend upon the strength of the spring, the speed at which the 35 drive is traveling and the weight of the carrier plus its load. As will be readily apparent, different conditions of operation will require springs of different strengths.

As the ratchet member 25 yields under the force 40 required to move the carrier either by impact or due to excessive load on the carrier, etc., the lever comprising the members 29 and 30, to which it is attached, always remains parallel with the direction of movement, but gradually moves toward 45 the right, as viewed in Fig. 3, that is, in a direction away from the carrier. If the impact is sufficient or if the force required to move the carrier exceeds a predetermined amount, the levers which 50 carry the ratchet member 25 will be moved to a position approximating that shown in dotted lines in Fig. 3, that is, until the ratchet member 25 slips off of or clears the end of the carrier bracket arm 31.

From the foregoing it will be apparent that the 55 objects of the invention heretofore enumerated and others have been accomplished and that a system of the character referred to has been provided in which the carrier pushed onto the same will be accelerated to the speed of the drive without subjecting the system to excessive strain and in which the drive will be readily disconnected from the carriers in the event the free forward movement thereof is interfered with for any reason. While the means for accomplishing these 60 results, in the preferred embodiment of the invention shown, is incorporated in the power drive, it will be readily apparent that this means can be easily incorporated in the carriers, if desired. In fact, in some instances this might be highly desirable. While the preferred embodiment of the 65 invention referred to has been herein illustrated and described in considerable detail, it will be readily apparent that the invention may be otherwise embodied, and it is to be understood that the 70 invention is not limited to the specific construc-

tion shown. It is the intention to cover hereby all adaptation, modification, and alternative constructions falling within the spirit and scope of the present invention, as defined by the following claims.

Having thus described my invention, I claim:

1. In a tramrail system of the character referred to, the combination of an overhead track, a carrier member supported on said track and movable therealong, a flexible driving member 10 paralleling said track, a driving member carried by one of said members and adapted to engage the other of said members, and resilient means for normally maintaining said driving member in operative position and carried by the member which 15 carries the driving member, said driving member being yieldable out of said operative position when the force required to propel said carrier exceeds a predetermined amount.

2. In a tramrail system of the character referred to, the combination of an overhead track, a carrier supported by said track and movable therealong, a flexible driving element paralleling said track, a driving member pivotally carried by 20 said flexible driving element and adapted to engage said carrier, and resilient means carried by said flexible driving element for normally maintaining said driving member in operative position, said driving member being yieldable out of said 25 operative position when the force required to propel said carrier exceeds a predetermined amount.

3. In a tramrail system of the character referred to, the combination of an overhead track, a carrier member supported on said track and movable therealong, a flexible driving member paralleling said track, a lever pivotally carried by one of said members, a pawl operatively connected to said lever and adapted to engage the other of said members, and resilient means carried by 30 the same member which carries said lever for normally maintaining said lever in a position normal to the direction of travel of said members, said resilient means permitting said lever to rotate to a position where said pawl no longer 35 engages said other member when the force required to propel said carrier member along said track exceeds a predetermined amount.

4. In a tramrail system of the character referred to, the combination of an overhead track, a carrier member supported on said track and 40 movable therealong, a flexible driving member paralleling said track, a pair of levers pivotally carried by one of said members and connected therewith at spaced points one behind the other, a link connected to the ends of said levers, a 45 pawl carried by said link and adapted to engage the other of said members, resilient means carried by said flexible driving member for normally maintaining said levers, in a position normal to the direction of travel of said members, said resilient means permitting said lever to rotate to a position where said pawl no longer engages said other member when the force required to propel 50 said carrier member along said track exceeds a predetermined amount.

5. In a tramrail system of the character referred to, the combination of an overhead track, a carrier supported on said track and movable 55 therealong, a flexible driving element paralleling said track, a pair of levers pivotally carried by said flexible driving element, said levers being connected to said flexible driving element at spaced points and one thereof being located behind the other, a link connected to the ends of 60

said levers, a pawl carried by said link and adapted to engage said carrier, resilient means carried by said flexible driving element for normally maintaining said levers in a position normal to the direction of travel of said flexible driving element while permitting the same to rotate to a position where said pawl no longer engages said carrier when the force required to propel said carrier along said track exceeds a predetermined amount.

6. In a tramrail system of the character referred to, the combination of an overhead track, a carrier supported on said track and movable therealong, a flexible driving element paralleling said track, a bracket connected to said flexible

driving element, a pair of levers pivotally carried by said bracket one behind the other, a link connected to the ends of said levers, a pawl carried by said link and adapted to engage said carrier one of said levers extending to opposite sides of its pivot, and resilient means connected to said bracket and to the end of said lever remote from said link for normally maintaining said levers in a position normal to the direction of said carrier while permitting the same to rotate to a position where said pawl no longer engages said carrier when the force required to propel said carrier along said track exceeds a predetermined amount.

MORRIS G. ROSENTHAL. 15
